FLORAL GREENHOUSE

Robert F. Rasmussen, Brooklyn Center, Minn., assignor
to The Technicraft Corporation, Minneapolis, Minn., a
corporation of Minnesota

Filed June 12, 1967, Ser. No. 7,867

Term of patent 14 years

(Cl. D35—3)

Fig. 1

FIG. 2

FIG. 3

FIG. 1 is a perspective view of a floral greenhouse showing my new design, the opposite sides are mirror images of the sides shown;

FIG. 2 is a perspective view with the hinged cover in an open position; and

FIG. 3 is a cross section taken substantially along the center transverse axis of FIG. 1.

The front and side panels are shaded to indicate a transparent surface and the rear panel is understood to represent a reflective surface.

The dominant features of my design reside in the portions shown in full lines.

This is a continuation-in-part of design application Serial No. D.62, filed Dec. 6, 1965 and now abandoned.

I claim:

The ornamental design for a floral greenhouse, substantially as shown and described.
